US00D343901S

United States Patent [19]

Anderson

[11] Patent Number: Des. 343,901

[45] Date of Patent: ** Feb. 1, 1994

[54] **CARDIOVERTER DEFIBRILLATOR CANNISTER**

[75] Inventor: **Kenneth M. Anderson**, Bloomington, Minn.

[73] Assignee: **Angeion Corporation**, Plymouth, Minn.

[**] Term: **14 Years**

[21] Appl. No.: **876,201**

[22] Filed: **Apr. 28, 1992**

[52] U.S. Cl. **D24/167; D24/155**
